UNITED STATES PATENT OFFICE.

MAX LEVITT, OF BROOKLYN, NEW YORK.

DESIGN FOR A LADY'S GARMENT.

Application filed January 9, 1929. Serial No. 29,550. Term of patent 3½ years.

To all whom it may concern:

Be it known that I, MAX LEVITT, a citizen of the United States, residing in the borough of Brooklyn, in the county of Kings, city and State of New York, have invented a new, original, and ornamental Design for Lady's Garment, of which the following is a specification, reference being had to the accompanying drawing, forming a part hereof.

Fig. 1 is a front view; and

Fig. 2 is a rear view of a coat showing my new design.

I claim:

The ornamental design for a lady's garment, as shown.

Signed at the city of New York, in the county of New York, State of New York, this 7th day of January, 1929.

MAX LEVITT.
